UNITED STATES PATENT OFFICE.

ADELMER M. BATES, OF CHICAGO, ILLINOIS.

LOADING APPARATUS.

1,060,154.

Specification of Letters Patent. Patented Apr. 29, 1913.

Application filed December 14, 1911. Serial No. 665,651.

To all whom it may concern:

Be it known that I, ADELMER M. BATES, a citizen of the United States, residing at Chicago, in the county of Cook and State 5 of Illinois, have invented a certain new and useful Improvement in Loading Apparatuses, of which the following is a specification.

My invention relates to machines for conveying filled bags and particularly to a machine for conveying filled cement bags to a rail-road car by means of which they are to be shipped.

A form of apparatus contained in my invention is illustrated in the accompanying drawings wherein—

Figure 1 is a side elevation; Fig. 2 a detail plan view; Fig. 3 a cross section with the bag filling machine shown in elevation; Fig. 20 4 a detail plan view of the delivery end; Fig. 5 a detail cross section. Fig. 6 a detail showing the modified form of stop.

Like parts are indicated by the same letter in all the figures.

25 A is a bag filling machine operated from the motor A¹ and adapted in this case to receive cement from the hopper A² and to fill a bag A³ standing on the platform A⁴. The machine is provided with means, in 30 this case a pusher A⁵, to push off the filled bag onto the conveying apparatus and the machine may be adapted to simultaneously fill a series of bags but should be timed or operated so that the filled bags are successively pushed off of the conveyer. E, B are framing portions and supports for the various parts of my conveyer. This conveyer consists of the endless belt C running over end pulleys C¹, C² and idlers C³, C⁴.

40 C⁴ is a belt tightener roller movably supported on the screw bars C⁵ in the usual manner.

D is a chute between the two sides of which the bags are received so that their 45 fall is broken, but the proportions of the parts are such that enough of the bag will contact the belt so that the belt while traveling will carry forward with it in succession the bags discharged upon it. The 50 details of arrangement of the belt and its several guiding and supporting and driving pulleys is of no material consequence and may be taken as here shown merely dia-grammatic.

55 E is a discharge apron pivotally attached to the frame portion at E¹ projecting out-

wardly beyond the end of the belt and is supported at its outer end when in use by the pivotally attached leg E². The upper end of the apron E is placed relatively high 60 up on the discharge end roller, C² so as to obviate any considerable drop of the discharge bag but when so placed there is danger that the somewhat loosely filled and always flexible or yielding cement bags will 65 be caught between the apron and the belt. To obviate this I provide a discharge roll F suitably supported in arms F¹ from the frame and driven by means of the pinion F² which meshes with the gear wheel F³ on 70 the shaft F⁴ which carries the pinion F⁵ which in turn meshes with the gear F⁶ on the shaft F⁷ which is driven by the sprocket wheel F⁸ from any desired source of power. On the shaft F⁷ is mounted the discharge 75 end roller C². This discharge roll is placed so as to prevent the catching of the bag between the belt and the apron and it eases the bag down from the belt to the apron so that the operator can easily pick up the bags 80 and drop them onto the truck which he manipulates within the car.

G, G are the arms of a stopping device. They are connected at their outer ends by the end G¹ which is inclined as shown to 85 prevent the bags from riding up on it while it stops the bags for the belt on which they travel is smooth enough to run under them. The two arms G, G are pivoted at G², G², and associate with the handle G³ whereby 90 the stopping device may be tilted in either direction, as indicated in Fig. 1.

G⁴ is a stop to limit the motion of the stopping device when moved toward its position of idleness.

95 G⁵ is a rope attached to the lower end of the handle G³ and passing forward is attached to the hook G⁶ so that its outer end may be within reach of the operator so that the operator in the car when his truck is 100 loaded or at any other time when he so desires or when there are enough bags beyond the stopping device to fill his truck can operate the stopping device and check the flow of bags until he is ready to receive 105 them again without stopping the motion of the conveyer.

In the modified form shown in Fig. 6 the discharge apron E is mitered as indicated at H and provided with a pivotally mounted 110 extension H¹ which may lie in the mitered portion of the apron in continuation of its

working surface or which may be held at right angles thereto by means of the handle H^2 in engagement with the spring lock H^3 at the will of the operator.

5 It will of course be understood that the parts are here shown more or less diagrammatically and incompletely although the drawings represent an operative structure and I wish the drawings to be taken in a 10 sense as diagrammatic or suggestive. Parts may be omitted of course or varied without departing from the spirit of my invention.

The use and operation of my invention have been explained but may be briefly re- 15 stated as follows. The bag conveying machine is preferably adapted to successively discharge bags upon the belt and where such bags are heavy, as in the case of cement, their fall onto the belt should be eased or 20 broken in some such manner as suggested. The car which is to be filled having been

properly placed on the siding opposite the conveyer, the operator throws the apron up 25 into position and secures it there by means of the leg, the belt driving mechanism being now thrown into operation the belt begins to travel in the direction indicated and it carries with it the bags which are successively fed to it, these bags being not 30 too tightly filled with heavy and inert material, such, for example, as cement, although of course the apparatus is applicable to the handling of bags of material other than cement. They lie upon the belt in a some- 35 what spread out condition. When they reach the discharge end of the belt they begin to pass over the discharge end roller and are received upon and drawn along by the small discharge roller. It will be under-

40 stood that the peripheral velocities of the discharge end roller and the discharge roll are approximately the same. This roll carries the bag over the break between the apron and the belt without causing it to be 45 dumped or turned over or disturbed in its position and so it moves gently and in proper condition for handling, onto the apron. Here it may be picked up or down- 50 wardly moved by the operator and be delivered to the truck. When the operator finds his supply of bags sufficient for the moment he will release the controller rope which permits the stopping device to fall 55 from the position shown in dotted lines to the position shown in full lines in Figs. 1 and 2. This arrests the flow of the bags and the belt slides under them. Any kind 60 of a suitable smooth surfaced belt may be used and I have even contemplated using a steel ribbon belt. The weight of the bags would hold the belt on or adjacent to its supporting idle rollers notwithstanding the

forward pull of the belt but of course any other arrangement accomplishing the same result may be substituted. The stopping 65 device having its stopping end backwardly inclined to the line of travel of the bags cannot get under the bags or have the weight of the last bag thrown upon it so as to make it impossible or difficult for the operator to 70 raise it which he will do by pulling on the controller rope when he desires the feed to be resumed. The apron is pivotally mounted and provided with means for adjusting its annular position in order that the height 75 of the discharge edge thereof may be adjusted to suit the convenience of the operator and in order that when it is desired to move the loaded car away and to move an empty car into line with the end of the belt, 80 this may be done by dropping the apron allowing it to swing outside of the line of the car.

The invention comprises means for continuously moving successively discharged 85 filled bags to a car or other receptacle means for temporarily arresting the flow or movement of such bags and means for delivering them without any great drop or fall, without disturbance of the bags and without 90 danger of their being pinched between the belt and the receiving apron.

I claim:

1. A filled-bag conveying machine comprising a conveying belt, a discharge apron 95 whose receiving end is pivotally mounted and in close proximity to the belt at the turn, and projects longitudinally beyond the belt, and a small discharge roll lying over and adapted to close the gap between the 100 belt and apron and intermediate their working surfaces so as to form part of the surface over which the bags proceed from the receiving end of the conveyer to the discharge end of the apron. 105

2. A filled-bag conveying machine comprising a conveying belt, a discharge apron whose receiving end is pivotally mounted and in close proximity to the belt at the turn, and projects longitudinally beyond the 110 belt, and a small discharge roll lying over and adapted to close the gap between the belt and apron and intermediate their working surfaces so as to form part of the surface over which the bags proceed from the receiv- 115 ing end of the conveyer to the discharge end of the apron, and a stop device adapted to intercept the bags and hold them while permitting the belt to slide under them.
